UNITED STATES PATENT OFFICE

110,406

DESIGN FOR A MONOPLACE PURSUIT AIRPLANE

Roscoe C. Wilson, Fairfield, and Louis R.
Koepnick, Dayton, Ohio

Application December 1, 1936, Serial No. 66,238

Term of patent 3½ years

To all whom it may concern:

Be it known that we, Roscoe C. Wilson and Louis R. Koepnick, citizens of the United States, residing at Fairfield, county of Greene, and State of Ohio, and Dayton, county of Montgomery, and State of Ohio, respectively, have invented a new, original, and ornamental Design for a Monoplane Pursuit Airplane, of which the following is a specification, reference being had to the accompanying drawings, forming part thereof, wherein:

Fig. 1 is a perspective view looking from the front and top of our design of airplane;

Fig. 2 is a top plan view of said airplane design in reduced scale;

Fig. 3 is a front elevational view of said airplane design in reduced scale; and

Fig. 4 is a side elevational view of said airplane design in reduced scale.

We claim:

The ornamental design for a monoplane pursuit airplane, as shown.

ROSCOE C. WILSON.
LOUIS R. KOEPNICK.
